UNITED STATES PATENT OFFICE.

THOMAS W. PORTER, OF CHELSEA, AND HENRY K. PORTER, OF BOSTON,
MASSACHUSETTS.

SPRING-SHACKLE.

SPECIFICATION forming part of Letters Patent No. 285,071, dated September 18, 1883.

Application filed December 9, 1880. (No model.)

To all whom it may concern:

Be it known that we, THOMAS W. PORTER, of Chelsea, and HENRY K. PORTER, of Boston, Massachusetts, have invented an Improved 5 Spring-Shackle, of which the following is a specification.

This invention relates to improvements in the shackles usually denominated "side-spring shackles," and which are employed to connect 10 the respective ends of the springs with the rocker or long head-block and the hind axle of the vehicle; and our invention consists in a shackle so constructed and arranged that it may be adjusted by lateral vibration to accommodate the shackle-link to springs arranged 15 with any desired degree of obliquity relatively to the axial line of the carriage.

In the annexed drawings, Figure 1 is a top or plan view of one shackle. Fig. 2 is a side 20 elevation of the same. Fig. 3 is a vertical section of the shackle, taken on line Y Z, Fig. 1, and showing the shackle as secured to the axle and axle-stock. Fig. 4 is a horizontal section taken as on line W X, Fig. 3.

25 In the drawings, A represents the hind axle, and B the axle stock or bed. C is the shackle-plate. D is the link, and E a tubular cross, which is pivoted to plate C, and which furnishes the pivotal support of link D.

30 Plate C is preferably formed with a central pin, l, which enters bed B, and secures the plate from lateral displacement. It is also formed with a back shoulder, c, and a front part or member, d, which shoulders against bed B. Upon part d are formed the ears e e, as shown.

The holes a a, formed, respectively, in shoulders c d, receive the rounded ends of the securing-clip b, as shown. This shackle-plate C 40 is an improvement upon that shown in Letters Patent No. 75,973, dated May 24, 1868, granted to said T. W. Porter, and it is not herein broadly claimed, but only in its improved form. Said tubular cross E is formed with 45 the tube f, which is arranged between and secured to ears e e by the pivot h, upon which the cross is arranged to be vibrated by the exertion of some force thereon. One of the tubular transverse bars m of link D is inserted and 50 secured in the horizontal tube g of cross E,

and to the other of said bars m the end of the spring is attached in the usual manner. This link is the same that is described and claimed in Letters Patent No. 196,478, dated October 23, 1877, issued to said H. K. Porter, and it 55 is not claimed herein, except in combination with the coacting parts. When the shackle is in place upon the axle, as shown, the cross E may be vibrated on its pivot h to such extent that the axis of its tube g shall be at 60 right angles to the vertical axis of the spring, whether the latter be arranged parallel to or at any desired degree of obliquity to the vertical axis—or fore and aft central vertical line—of the carriage, and so that said tube g shall 65 be parallel to the eye formed at the end of such spring, whereby link D, when seated in tube g, will be in proper position to be connected with such spring. By thus forming a shackle with a pivoted link-holder, each shackle may 70 be used for parallel or oblique springs, and in the latter case for either a "right" or "left" hand shackle; and, besides, the same shackles are available for all degrees of obliquity of the springs, which obliquity may result from varying 75 the relative length and width of the carriage or from other causes, and to supply which (but for such pivotal link-holder) would require as many different patterns of shackle-plates as there might be variations in degrees of obliquity of the springs. 80

We claim as our invention—

1. The plate C, formed with the following elements or parts, to wit: a seat to receive axle-bed B, passages to receive the ends of the axle-securing clip b, and the perforated ears e, to receive and support tubular cross E, thereto pivoted, and arranged to receive the shackle-link, substantially as specified. 85

2. The combination, with plate C, formed 90 as specified, of tubular cross E, thereto pivoted, substantially as specified.

3. The combination of plate C, tubular cross E, and link D, all constructed and combined to operate substantially as specified.

THOMAS W. PORTER.
HENRY K. PORTER.
